UNITED STATES PATENT OFFICE.

JOHN STEWART McPHERSON, OF COLUMBUS, OHIO, ASSIGNOR TO THE BUCKEYE STEEL
CASTINGS COMPANY, OF COLUMBUS, OHIO.

BRAKE HANGER.

Application filed July 16, 1925. Serial No. 44,044.

This invention relates to brake hangers for car trucks and has for its object the provision of a hanger and a hanger bracket of novel construction whereby the brake mechanism may be adapted to a track of wider or narrower gage without material change in the structure. There are many localities in which there is no universal standard railroad gage and in a great many cases the gage now used is appreciably wider than the gage which, it is believed, will eventually be adopted. In anticipation of the adoption of the narrower uniform gage, it is proposed to build trucks so that by moving the wheels on each axle closer together they will fit the narrower gage track, the original journal centers being maintained so that the principal parts of the original truck can be used,—the only new parts needed being the brake beams. To provide a hanger bracket on the truck frame that will support the usual type of U-shaped brake hanger at its proper location, in case of the narrower gage, requires an extremely long overhang. A specific object of the present invention is to minimize the overhang and, at the same time, provide a substantial support for the hanger when arranged for either the wider or the narrower gage. The stated objects and other objects which will hereinafter incidentally appear are attained in the use of such a mechanism as is illustrated in the accompanying drawings and the invention resides in certain novel features which will be particularly pointed out in the appended claims.

In the drawings, Figure 1 is a plan view of a portion of a truck having the present invention embodied therein;

Figure 2 is a view in elevation, and

Figures 3 and 4 are views partly in section and partly in elevation showing different positions of the hanger.

The truck includes a bolster 1 having each end carried by a side frame 2. On the inner side of each side frame, near to but out of the vertical range of the bolster, is an inwardly projecting hanger bracket or arm 3 which is preferably cast integral with the side frame and the inner end of which is so located as to cross the vertical plane of the car wheels on the same side of the truck. On the under side of this arm or bracket 3, at and near the inner end thereof, are three

equidistant lugs 4 extending across the full width of the arm longitudinally of the truck in parallel relation. Openings 5 are formed through these lugs below the bracket in axial alinement to receive a bolt or pin 6 by which the brake hanger 7 is suspended, the hanger being of the bail type with eyes 8 at the upper ends of its side members to be engaged by the suspending pin or bolt. It will be noted that one side member, 9, of the hanger is straight and rises from the lower end member 10 at a right angle thereto while the other side member has a lower portion 11 extending from the end member 10 at a right angle thereto and an upper portion 12 which converges toward the side member so that the distance between the eyes 8 or the width of the upper end of the hanger is less than the width of the lower end of the hanger which is engaged with the brake head in the usual manner, that is to say, one side of the hanger is offset relative to a vertical line passing medially between the eyes 8.

In practice, when the truck is running on the wider gage track, the hanger is arranged as shown in Figure 3 with its straight side between the innermost lug 4 and the center lug and its offset side at the outer side of the outermost lug. When the truck is to run on the narrower gage track, the suspending pin or bolt is removed and the hanger is shifted transversely of the truck and also turned so that its offset side will become the inner side, as shown in Figure 4. The straight side of the hanger is then engaged between the center lug 4 and the outer lug while the offset side will be disposed against the inner side of the innermost lug, the suspending pin or bolt being inserted as before to secure the hanger. It will be seen that by very slight and simple manipulation, the full displacement of the center of the brake head seat on the hanger necessary to accommodate both gages will be obtained, the overhang is minimized, and a substantial anchorage for the hanger is provided preventing end-wise movement of the brake beam in either adjustment.

Having fully described my invention what I claim as new and desire to secure by Letters-Patent, is:—

1. In a car brake hanger mechanism, the combination of a car truck side frame, a hanger bracket on the side frame, a brake

hanger, and means whereby the hanger may be suspended at a plurality of selected distances from the side frame.

2. In a car brake hanger mechanism, the combination of a car truck side frame, a hanger bracket projecting laterally from the side frame, a brake hanger, means for suspending the hanger at a plurality of selected distances from the side frame, and means for preventing movement of the hanger along the bracket.

3. In a car brake hanger mechanism, the combination of a car truck side frame, a hanger bracket projecting laterally from the side frame and having a plurality of depending lugs on its under side at its inner end,

a brake hanger, and means for suspending the hanger on selected lugs.

4. In a car brake hanger mechanism, the combination of a car truck side frame, a hanger bracket projecting laterally from the side frame and having a plurality of lugs on its under side, a bail constituting a brake hanger and having one side offset at its lower end relative to the other side, and means for suspending the bail from the lugs on the bracket the sides of the bail being disposed selectively at either side of the respective lugs.

In testimony whereof, I have signed this specification.

JOHN STEWART McPHERSON.
